Primary Examiner — Rosemary K Tarcza*Assistant Examiner* — Seth David Kumpf(74) *Attorney, Agent, or Firm* — Maginot, Moore & Beck LLP(57) **CLAIM**

The ornamental design for a battery, as shown and described.

DESCRIPTION

FIG. 1 is a perspective view of a battery showing our new design;

FIG. 2 is a right side elevational view of the battery of FIG. 1;

FIG. 3 is a left side elevational view of the battery of FIG. 1;

FIG. 4 is a front side elevational view of the battery of FIG. 1;

FIG. 5 is a rear side elevational view of the battery of FIG. 1;

FIG. 6 is a top plan view of the battery of FIG. 1; and, FIG. 7 is a bottom plan view of the battery of FIG. 1.

The broken lines shown in the drawings illustrate portions of the battery that form no part of the claimed design.

1 Claim, 4 Drawing Sheets(56)
